UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO, CANADA.

MANIFOLDING SALES-BOOK.

1,108,487

Specification or Letters Patent. Patented Aug. 25, 1914.

Application filed July 17, 1912. Serial No. 709,856.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to manifolding sales books.

One of the objects of this invention is to provide a simple and practical sales book for producing records of any transaction.

A further object is to provide an automatic manifolding sales book which will be cheap to manufacture and convenient in use.

20 A further object is to provide a practical and efficient automatic manifolding sales book in which the leaves will be firmly held while making inscriptions thereon.

Other objects will be in part obvious and 25 in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing wherein is shown one of the various possible embodiments of this invention, Figure 1 is a plan view of the complete device, and Fig. 2 is a side elevation.

Similar reference characters refer to similar parts throughout the several views of 40 the drawing.

Referring now to the drawing in detail, 1 denotes a support or back to which is secured by means of staples 2 a plurality of sets of original and duplicate leaves 3 and 4, respectively. These leaves are connected at their lower ends, the original leaf being folded back on and above the duplicate leaf. A line of perforations 5 in the fold permits the leaves to be readily detached. Each 50 duplicate leaf is longer than the original leaf of the set, whereby the same may be conveniently bound. A second line of perforations 6 is provided adjacent the stub, whereby the duplicate leaf may be readily detached therefrom. The upper end of

each original leaf extends slightly beyond the line of perforations 6 whereby it is firmly held or pinched by the stub 7 of the duplicate leaf thereabove or the binding 8 in the case of the top set. By binding the 60 leaves in this manner both the original and duplicate leaves will be firmly held in position while the inscription is being made thereon, thereby producing more perfect duplicate records. The back of each original leaf is carbonized throughout substantially its entire surface as indicated by the heavy line and also the torn portion 9. By means of this construction it is unnecessary to use carbon sheets and the book may 70 be operated more rapidly and efficiently.

In order to prevent inscriptions being reproduced on the lower sets of leaves, the rear cover 1 is folded back on itself and the upper part 10 thereof provides a separator 75 plate which may be inserted beneath the top set of leaves. When the book is not in use the separator plate is drawn out and laid over the top set of leaves, thereby forming a top cover for the book.

While it is thought that the operation of a device of this character will be clear from the above description, a brief statement thereof is substantially as follows: The separator plate 10 is inserted beneath the top 80 set of original and duplicate leaves and the inscription recorded upon the ruled lines. This inscription is reproduced on the duplicate leaf 4 by reason of the carbonized surface 9. After completing the inscription 90 the set of leaves is grasped between the thumb and finger and torn from the stub along the perforated lines 6. The original and duplicate leaves are then separated along the line 5 and disposed of as desired. 95 If a subsequent transaction is to be recorded the separator plate is inserted beneath the next set of leaves and the book is again ready for operation. If it is necessary to make an erasure, the end of the original 100 leaf may be easily slipped out from its secure position beneath the stub of the preceding duplicate leaf and the changes made as may be necessary.

It is thus seen that this invention provides an automatic sales book which is simple and compact and may be easily and quickly operated and is adapted to accomplish, among others, all the objects and advantages above set forth.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

10 Having described my invention, what I claim as new and desire to secure by Letters Patent is:—

1. In a device of the character described, in combination, a plurality of sets of original and duplicate leaves, the duplicate leaves being bound together along one end edge and the free end edge of each original leaf being temporarily secured by the stub portions of the adjacent leaves.

20 2. In a device of the character described, in combination, a plurality of sets of leaves connected at one end, the opposite ends of the alternate leaves being bound together at their stub portions, the free ends of the other alternate leaves being temporarily secured independently of the binding means.

30 3. In a device of the character described, in combination, a plurality of sets of leaves connected at one end, binding means for the opposite ends of the alternate leaves, the free ends of the other alternate leaves being temporarily secured beneath the stub of the leaves thereabove, the back of each of said last-mentioned leaves being carbonized.

40 4. In a device of the character described, in combination, a plurality of sets of original and duplicate leaves connected at one end, the opposite ends of the duplicate leaves only being bound together to form a stub, the free ends of the original leaves being temporarily secured to the stub, and manifolding means between the sets of leaves.

50 5. In a device of the character described, in combination, a plurality of sets of original and duplicate leaves, the leaves of each set being connected at one end and the opposite end of the duplicate leaves being bound together to form a stub, and lines of perforation separating the stub from the duplicate leaves, the free end of each original leaf extending beyond the line of perforations to be temporarily retained between the stub portions of the duplicate leaves.

60 6. In a device of the character described, in combination, a plurality of sets of original and duplicate leaves, the leaves of each set being connected at one end and the opposite end of the duplicate leaves being bound together to form a stub, and lines of perforation separating the stub from the duplicate leaves, the free end of each original leaf extending beyond the line of perforations to be temporarily retained between the stub portions of the duplicate leaves,

the back of each original leaf being carbonized.

7. In a device of the character described, in combination, a plurality of sets of original and duplicate leaves, the leaves of each set being connected at one end, and the opposite end of the duplicate leaves being bound together to form a stub, lines of perforation separating the stub from the duplicate leaves, the free end of each original leaf extending beyond the line of perforations to be temporarily retained between the stub portions of the duplicate leaves, manifolding means on the back of each original leaf, and a separator plate adapted to be inserted beneath the top set of leaves.

8. In a device of the character described, in combination, a plurality of sets of original and duplicate leaves, the leaves of each set being connected at one end and the opposite end of the duplicate leaves being bound together at their stub portions, lines of perforation separating the stubs from the duplicate leaves, the free end of said original leaf extending beyond the line of perforations to be temporarily retained between the stub portions of the duplicate leaves, manifolding means on the back of each original leaf, a rear cover for said sets of leaves, and a separator plate adapted to be inserted beneath the top set of leaves.

9. In a device of the character described, in combination, a support, a pad mounted thereon comprising a plurality of sets of original and duplicate leaves, the duplicate leaves extending beyond the adjacent edges of the original leaves to form stub portions, means for securing the duplicate leaves only to the support, weakening lines near the end of each duplicate leaf whereby the leaves may be separated from the pad, manifolding means associated with each set of leaves, and means connected with said support for preventing inscriptions being reproduced upon the sets of leaves beneath the top set.

10. In a device of the character described, in combination, a support, a pad mounted thereon comprising a plurality of long and short leaves alternately arranged, the longer leaves only being bound to said support and the free ends of the shorter leaves adjacent the bound edge of the longer leaves being temporarily secured thereby independently of the binding means.

11. In a device of the character described, in combination, a support, two kinds of leaves mounted thereon, one kind being longer than the other and the leaves of said kinds being alternately arranged, and means for binding the edges of the longer leaves to said support, the free end edges of the shorter leaves adjacent the bound edges of the longer leaves being temporarily secured thereby independently of the binding means.

12. In a device of the character described,

in combination, a support, two kinds of leaves mounted thereon, one kind being longer than the other and the leaves of said kinds being alternately arranged, means for binding the edges of the longer leaves to said support, the edges of the shorter leaves adjacent the bound edges of the longer leaves being temporarily secured thereby independently of the binding means, and mani-
10 folding means associated with each shorter leaf, whereby the record is reproduced on the longer leaf therebeneath.

13. In a device of the character described, in combination, a support, two kinds of leaves mounted thereon, one kind being longer than the other and the leaves of said kinds being alternately arranged, means for binding the edges of the longer leaves to said support, the edges of the shorter leaves
15 adjacent the bound edges of the longer leaves being temporarily secured thereby in-
dependently of the binding means, mani-
folding means associated with every other leaf, whereby the record is reproduced on the
20 next leaf therebeneath, and means adapted
25 to be inserted beneath the top pair of leaves

for preventing the inscription from being reproduced upon the leaves therebelow.

14. In a device of the character described, in combination, a plurality of original and 30 duplicate leaves, the leaves of one kind hav-
ing stub portions, and means for binding the stub portions together, the adjacent ends of the other kind of leaves being pinched. 35 between the stub portions of the first men-
tioned leaves.

15. In a device of the character described, in combination, a plurality of long and short leaves alternately arranged, the longer leaves projecting beyond the shorter leaves 40 at one end, a support, and means for secur-
ing the longer leaves to the support, the free ends of the shorter leaves being pinched be-
tween and temporarily held by the bound 45 projecting ends of the longer leaves.

In testimony whereof I affix my signature, in the presence of two witnesses.

EDWARD KIRBY BOTTLE.
